UNITED STATES PATENT OFFICE.

STANLEY RICE CURTIS, OF ROYAL OAK, MICHIGAN.

DRINKING-FOUNTAIN.

1,346,006.

Specification of Letters Patent.

Patented July 6, 1920.

Application filed May 29, 1918. Serial No. 237,347.

To all whom it may concern:

Be it known that I, STANLEY R. CURTIS, a citizen of the United States, residing at Royal Oak, in the county of Oakland and 5 State of Michigan, have invented new and useful Improvements in Drinking-Fountains, of which the following is a specification.

This invention relates to a drinking fountain, and the object is to provide means whereby a fountain of this type may be used for advertising purposes.

A further object is to provide in connection with a fountain including the usual bowl having an inlet and outlet, and means for controlling the inlet and outlet, an inner bowl of transparent material under which a sheet or card bearing advertising matter may be located.

20 A still further object is to provide a device of the type indicated including a shield with an inwardly and downwardly extending flanged portion adapted to overhang the edge of the bowl and the advertising matter.

With the foregoing and other objects in view, the invention consists in the novel construction, combination, and arrangement of elements hereinafter described and 30 claimed.

In the drawings, Figure 1 shows a drinking fountain in elevation and vertical section, with my invention applied thereto; Fig. 2 is a detail view, showing a protecting element with an overhanging flange, and Fig. 3 is a vertical section of the transparent element, or inner bowl.

In carrying out my invention I employ a bowl 10, which may be of substantially 40 the usual construction, and which is provided with a water inlet and outlet, and controlling means whereby the supply of water is governed. The general construction is shown more or less conventionally, a nozzle member being designated 12. The standard supporting the bowl is designated 14 and is provided with a base 15.

Within the bowl 10 is a supplemental bowl of glass or other suitable transparent

substance, this element being designated 16 50 and having a central flange 18 surrounding the opening 19, the flange engaging a gasket 21 for the purpose of effecting a water tight connection. Bowl 10 is provided with an annular channel receiving gasket 21 and 55 flange 18.

The sheet or card containing advertising matter is shown at 22 and is located between the inner and outer bowls.

A shield designated 24 is provided with 60 inwardly and downwardly turned flanges 25 extending over the edge of the two bowls. The device as a whole adds to the appearance, and protects the edge portions of the bowls.

65 It is obvious that any suitable material may be employed in the construction of the various elements of the device, and I do not limit myself in that respect or in connection with the details of construction 70 specified.

What is claimed is:

1. In a device of the class described, a standard, a bowl mounted thereon, said bowl having a lower central outlet opening 75 and an annular channel surrounding the opening, an inner bowl of transparent material within the bowl first named and having a central opening and an annular flange projecting from the edges of the walls of 80 the opening into the aforesaid channel, packing material between the flange and the walls of the channel, and a display sheet between the walls of the bowls and protected by the joint effected between the 85 flange and the channel.

2. In a device of the class described, a bowl provided with a water outlet and inlet, an inner bowl of transparent material spaced from the outer bowl, a sheet of advertising material between the bowls, said inner bowl being provided with a flange and with an opening, and means for effecting a water tight connection between the flange and the inlet for the bowl first named 95

In testimony whereof I affix my signature.

STANLEY RICE CURTIS.
